CLAIM

The ornamental design for a container for dispensing material, as shown and described.

DESCRIPTION

FIG. 1 is a front perspective view of a container for dispensing material in accordance with the present design; FIG. 2 is a left side elevational view thereof, the right side elevational view being a mirror image thereof; FIG. 3 is a front side elevational view thereof, the rear side elevational view being a mirror image thereof; FIG. 4 is a top plan view thereof; FIG. 5 is a bottom plan view thereof; and, FIG. 6 is a front side elevational exploded view thereof. The broken lines shown in the drawings illustrate portions of a container for dispensing material that form no part of the claimed design.

1 Claim, 4 Drawing Sheets
